UNITED STATES PATENT OFFICE.

WILLIAM H. MINER, OF CHAZY, NEW YORK.

DRAFT-RIGGING FOR RAILWAY-CARS.

1,255,907.

Specification of Letters Patent. Patented Feb. 12, 1918.

Original application filed April 18, 1914, Serial No. 832,689. Divided and this application filed September 28, 1915. Serial No. 53,111.

To all whom it may concern:

Be it known that I, WILLIAM H. MINER, a citizen of the United States, residing at Chazy, in the county of Clinton and State 5 of New York, have invented a certain new and useful Improvement in Draft-Riggings for Railway-Cars, of which the following is a full, clear, concise, and exact description, reference being had to the accompanying 10 drawings, forming a part of this specification.

This invention relates to improvements in draft riggings for railway-cars, and this application constitutes a division of my application 15 832,689, filed April 18th, 1914, for improvements in draft riggings for railway cars.

The object of the invention is to provide an improved draft rigging for railway cars 20 and more particularly improved stop members.

In the drawing forming a part of this specification, Figure 1 is a longitudinal vertical sectional view of a draft rigging showing 25 my improvement in connection therewith. Fig. 2 is a vertical transverse sectional view taken substantially on the line 2—2 of Fig. 1. And Fig. 3 is a detailed perspective showing a section of one of the stop 30 members with the novel strengthening or bracing means attached thereto.

In said drawing, 10—10 denote the center or draft sills of a car, 11 the draw-bar and 12 the combined friction shell and spring 35 casing. The member 12 has a friction cylinder proper 13 and a spring casing proper 14. Coöoperating with the cylinder 13 are friction shoes 15 and wedge 16. Mounted within the spring casing 14 are vertical twin ar- 40 ranged main springs 17—17, each consisting of a heavy outer coil and a nested inner lateral coil. At the front ends of the spring 17 is a movable follower 18 having a forwardly extended cylindrical flange 19 which 45 slides within the cylinder 13. Interposed between the follower 18 and the friction shoes is a preliminary spring 20, and the friction 50 elements, preliminary spring and follower 18 are held in assembled position by means of a bolt 21. The rear end of the spring casing 14 is open and has slidably mounted therewithin a rear follower 22, said follower 22 having a rearward extension 23 through 55 which extends a key 24. The key 24 is slidably mounted within suitable elongated

slots in the draft members 10 and said key is operatively connected with the draw-bar 11 by means of links 25 and coupler key 26, the latter also sliding in elongated slots in the draft members 10. The side walls of the 60 spring casing 14, at their rear ends are also slotted as indicated at 27 to accommodate the forward movement of the key 24. Where the spring casing 14 unites with the friction cylinder 13, shoulders 28 are formed 65 which engage the front stops, hereinafter described. All of the foregoing parts are the same as those shown and described in my said application 832,689, to which reference is hereby made for a more detailed 70 description of the operation of the gear.

The gear proper is supported between an upper stop member A and a lower stop member B, each of said members A and B, as shown, being in the form of a commercially 75 shaped channel iron, the member A having the flanges 29 thereof extended upwardly and riveted or otherwise suitably secured to the members 10, whereas the member B has its flanges 30 turned downwardly and de- 80 tachably secured to the draft members 10 as by bolts 31 or other suitable means. Each of the members A and B has a vertically ar- 85 ranged opening 32 therein within which is adapted to be received the spring casing 14. To strengthen the members A and to 90 also form more efficient stop shoulders, each of the transversely extending front and rear portions 33 and 34 of the members A is pro- 95 vided with a substantially U shaped clip 35 having parallel arms 36—36 fitting over the sections of the members A and B and se- 100 cured thereto as by rivets 37—37. The inner faces of the clips 35 are vertically elongated, as clearly illustrated in Figs. 1 and 3 to 95 thereby provide a wider bearing for the spring casing an'l the rear follower 22. With this construction, I form rigid front and rear stop shoulders, the same being so arranged as to minimize any tendency of 100 the web portions of the channels A and B being bent or turned.

As most clearly shown in Fig. 2, the spring casing is provided with longitudinally extending flanges 38—38 on the sides 105 thereof which rest upon flanges 39—39 struck upwardly from the web portion of the lower channel stop member B.

In assembling the device, the stop mem- 110 ber A is first permanently secured to the

draft members with the clips 35 attached thereto after which the links and gear proper are inserted, the stop member B being finally attached to the sills. The whole 5 structure affords an efficient gear and one which may be readily inspected for repairs, etc.

I claim:

1. In a draft rigging for railway cars, 10 stop members comprising upper and lower members, and provided with vertical slots adapted to receive a draft gear, the members forming the ends of the slots being provided with a U shaped clip forming stop 15 shoulders for the draft gear.
2. A stop member for draft riggings

comprising a commercially shaped beam having an opening therein adapted to receive a draft gear, the edges of said opening at the ends of the gear being reinforced 20 by U shaped clips forming shoulders.

3. A stop member for draft riggings, comprising a channel member having an opening through the web thereof, and U shaped clips secured to the web at the ends 25 of said opening, said clips each having a wide bearing inner face adapted to form a stop shoulder.

WILLIAM H. MINER.
